UNITED STATES PATENT OFFICE.

LEWIS G. O'DONNELL, OF COSCOB, CONNECTICUT.

TEMPERATURE-REGULATOR.

1,355,250.

Specification of Letters Patent. Patented Oct. 12, 1920.

Application filed July 17, 1919. Serial No. 311,668.

To all whom it may concern:

Be it known that I, LEWIS G. O'DONNELL, a citizen of the United States, residing at Cos Cob, Fairfield county, State of Connecticut, have invented new and useful Improvements in Temperature-Regulators, of which the following is a specification.

The object of this invention is to provide an automatic temperature regulator directly connected with a valve whereby the passage of liquids, gases and the like is controlled in an efficient and positive manner.

A further object is to provide a temperature regulator comprised of essentially simple parts adapted for long and continued service and which is extremely sensitive in its operation.

A still further object is to provide means whereby, if the regulator elements become damaged or deranged, the valve will become opened and remain open thereby avoiding danger which might otherwise occur.

These and other like objects, which will become more fully apparent as the description progresses, are attained by the novel construction and combination of parts hereinafter described and shown in the accompanying drawings, forming a material part of this disclosure, and in which—

30 Figure 1 is a side elevational view of a water circulating system as used in connection with a conventional type of internal combustion motor, and indicating the application of the invention.

35 Fig. 2 is an enlarged vertical sectional view taken through a temperature regulator made in accordance with the invention.

Fig. 3 is a further enlarged transverse sectional view showing one of the operative 40 double diaphragm elements used in connection therewith, and

Fig. 4 is a perspective view showing the diaphragm supports, and connecting means combined therewith.

45 Referring to the drawings in detail, the numeral 10 designates the body or casing of a four cylinder, internal combustion motor, the same containing the rotary parts thereof, and which energize the fly wheel 11 at one end. The cylinders 12 extend upward into cooling jackets 13, which are maintained in a relatively cool condition by water circulation, the water entering through the supply pipe 14, leading from 50 the radiator 15, supplied through the filling

nozzle 16, which is arranged at the top of the radiator in the usual manner.

The heated water is returned to the radiator 15 through the pipe 17 and interposed in the connection therebetween is an embodiment of the invention, the lower element of which is engaged direct with a coupling 18 on the end of the return pipe, while the discharge end of the regulator is engaged with the radiator at a point near 65 its top. See Fig. 1.

Engaged with the coupling 18 is an angularly disposed tube 19, having a level, expanded upper end 20, merging into an outer annular flange 21, upon which rests a similar 70 flange 22, these flanges being firmly engaged together by a plurality of spaced screw bolts 23.

Formed with the flange 22 is a cylindrical casing 24, partially surrounded at its upper 75 end by an extending flange 25, upon which rests the correspondingly shaped flange 26, formed with a valve casing 27, from which integrally extends an angular tube 28, the same being adapted to engage with the radiator 80 15, the tubes 19 and 28 being extended in opposite directions but in a substantially parallel plane.

The flanges 25 and 26 are secured together by screws 29, except in the vicinity of the 85 tube 28, where relatively long bolts 30 are passed through the flanges 21 and 22 and are threaded into the valve flange 26 direct.

Engaged in a screw-threaded opening formed in the upper portion of the valve 90 chamber 27 is a flanged bonnet 31, from which extends a central screw-threaded nipple 32, the same engaging a tubular cap 33 having an integral solid cover portion.

Formed in the lower level wall 34 of the 95 valve chamber, centrally over the casing 24, is a conical valve seat 35, and fitted thereto is a beveled edge of disk valve 36, fixed upon a sleeve 37, secured to a valve stem 38, the stem passing through a central opening in 100 the bonnet 31 and a recess 39 formed in the nipple 32.

Resting in the bottom of the recess 39 is the lower end of a coiled extension spring 40 encircling the stem 38 and exerting pressure against the hub of a milled nut 41, suited to the screw-threaded upper portion of the stem in such manner that the tension of the spring may be varied by actuating the nut.

Formed with the sleeve 37 is a head 43, fixed upon a circular spacing block 44 firmly engaged with the upper member 46 of a pair of thin flexible metallic diaphragms which are firmly united at their peripheries in a pliable metallic band 48, over which is spun or otherwise secured a ring 49 having in-turned flanged elements of substantially U section, the arrangement being such as to present a joint around the periphery of each of the several pairs of diaphragms each of which have undulating annular faces adapted to act in a resilient manner.

A central opening 50 is formed in each 15 of the diaphragms 46 and 47, adjacent to which are tightly secured washers 51, their central openings 52 being in register. The lowermost washer in the row is secured centrally on the upper side of a cross shaped 20 member having opposed pairs of arms 53 and 54, the last named arms containing an inner closed longitudinal passage 55, having a vertical central opening 56, registering with the openings 50 and 52, other openings 25 57 passing up through the arms 54 near their ends which, like the arms 53, are provided with raised lugs 58 at their terminals.

This cross shaped element rests upon an 30 interior flange 59 formed in the plane of the cylinder flange 22, the flange 59 constituting a partial partition or wall across the passage through the end of the pipe 19. The cross arms being held upon the extending flange 59 by screws 60, the arm 53 of 35 the cross-shaped element being provided with holes 53^a for this purpose.

Resting upon the upper surface of the cross arms, and held in position by the lugs 58, is a cylinder having inner and outer 40 walls respectively 61 and 62 hermetically closed at both ends, the cylinder extending upward coincident with the uppermost of the row of diaphragms. The annular space 45 63 between the cylinder walls constitutes a tank or reservoir and is in communication with the openings 57 by the hollow plugs 64, and also with the interior of the several diaphragms by the opening 56 containing the central hollow plug 65.

50 The annular tank and also the several diaphragms having been partially filled with a medium subject to expansion and contraction, according to the temperature, and the parts having been hermetically 55 sealed the device is ready for use.

The medium preferable to employ is ordinary atmospheric air, exhausted to produce a negative pressure or partial vacuum, capable of normally drawing the sides of 60 each pair of diaphragms nearly or quite in contact when in a relatively cool condition.

This vacuum obviously also exists in the reservoir or tank 63, here shown as a hollow annulus, (although not necessarily limited 65 to such form) interconnected with the dia-

phragms in any practical manner, the purpose being to present a relative large volume inclosed in walls having extensive superficial areas directly exposed to the effects of the exhaust water used in cooling the 70 cylinders, thereby securing results unattainable by diaphragms alone.

When the water heated by the exhaust gases from the motor, pass through the regulator, the same coming in contact with 75 the surfaces of the tank and the diaphragms, the medium therein is caused to expand, raising the valve in an obvious manner, as shown in Fig. 2, and permitting the heated water to pass through the pipe 28 into the 80 radiator.

Should however the water be insufficiently heated to expand the medium in the diaphragms, then, due to their inherent resilience and the partial vacuum therein they 85 will close, drawing the valve to its seat and preventing the water from escaping until the same shall have obtained a definite high temperature.

Should a leak occur in the diaphragms or 90 tank so as to render them inoperative, by destroying the partial vacuum thereof, the spring 40 will raise automatically the valve 36, permitting free passage of the water and preventing damage being done the motor. 95

It will be evident that the simplicity of construction, small space required and avoidance of danger, should inoperativeness occur, present points of obvious practicability and effectiveness. 100

The foregoing disclosure however, is to be regarded as descriptive only and not as restrictive or limitative of the invention, of which obviously embodiments may be constructed including many minor modifications, without departing from the general spirit and scope herein indicated and claimed as follows:

1. In a temperature regulator, the combination with a valve chamber, inlet and outlet connections thereto, and a valve operative in said valve chamber, of a casing interposed between said valve chamber and said inlet, a series of intercommunicating pairs of resilient diaphragms engaging between the bottom of said casing and said valve, a reservoir circumjacent to said diaphragms, there being hollow connections between said reservoir and said diaphragms, said elements being hermetically sealed and a partial vacuum formed therein adapted to contract said diaphragms and close said valve when cool, and to expand the diaphragms and raise the valve when heated. 110

2. In a temperature regulator, the combination with a valve chamber, inlet and outlet connections thereto, and a valve operative in said valve chamber, of a cylindrical casing engaged between said chamber and said inlet, a plurality of double faced resili- 125

- ent diaphragms arranged in spaced relation in said casing, hollow connections between the opposed faces of said diaphragms, operative connections between the uppermost of 5 said diaphragms and said valve, one or more reservoirs surrounding said diaphragms, hollow connections between said reservoirs and said diaphragms, said reservoirs and diaphragms being sealed after the air has 10 been partially extracted therefrom whereby the faces of said diaphragms are drawn toward each other when cool and forced apart when heated.
3. In a temperature regulator, the combination with a valve chamber, inlet and outlet connections thereto, and a valve operative in said valve chamber, of a casing interposed between said valve chamber and said inlet, a plurality of interconnected resilient dia- 15 phragms in said casing, said diaphragms being arranged in hermetically sealed pairs from which the air has been partially extracted, a cross-shaped element fixed in said casing containing internal recesses, a thin 20 walled reservoir encircling said diaphragms secured on said cross and communicating through the recess with the diaphragms whereby the negative pressure is equalized, and operative connections between said dia- 25
- phragms and said valve whereby the latter 30 is raised or lowered according to the fluctuation of pressure in said diaphragms and reservoir caused by changes of temperature.
4. In a temperature regulator, the combination with a valve chamber having an outlet, a bonnet engaged on said chamber and a removable cap on said bonnet, of a cylindrical casing below said chamber, an inlet thereto, a vertical row of double faced dia- 35 phragms interconnected in series in said cas- 40 ing, a reservoir in said casing communicating with said diaphragms, said reservoir and diaphragms being sealed and containing an expansible medium, a valve in said chamber operatively engaged by said diaphragms, a 45 stem for said valve extending into said cap, and an adjustable tensioned spring in said cap adapted to normally raise said valve, opposing the contractive effects of said dia- 50 phragms when uncontrolled by the medium therewithin.

In testimony that I claim the invention above set forth I affix my signature in presence of two witnesses.

LEWIS G. O'DONNELL.
